UNITED STATES PATENT OFFICE.

JAMES E. NISBET, OF JACKSONVILLE, ALABAMA.

FAN.

1,210,828.

Specification of Letters Patent.

Patented Jan. 2, 1917.

Application filed December 11, 1915. Serial No. 66,369.

To all whom it may concern:

Be it known that I, JAMES E. NISBET, a citizen of the United States, residing at Jacksonville, in the county of Calhoun and State of Alabama, have invented certain new and useful Improvements in Fans, of which the following is a specification, reference being had to the accompanying drawings.

10 This invention relates to certain improvements in fans and has relation more particularly to a device of this general character especially designed and adapted for use in connection with a rocking chair; and 15 it is an object of the invention to provide novel and improved means whereby the fan is caused to automatically operate upon oscillation of the chair.

The invention consists in the details of 20 construction and in the combination and arrangement of the several parts of my improved fan whereby certain important advantages are attained and the device is rendered simpler, less expensive and otherwise 25 more convenient and advantageous for use, all as will be hereinafter more fully set forth.

The novel features of the invention will be carefully defined in the appended claims.

30 In order that my invention may be the better understood, I will now proceed to describe the same with reference to the accompanying drawings, wherein—

Figure 1 is a view in side elevation illustrating an embodiment of my invention in applied position; Fig. 2 is an enlarged fragmentary sectional view taken substantially on the line 2—2 of Fig. 1; Fig. 3 is a fragmentary view in top plan of my invention 40 as herein disclosed, with the limiting spring omitted; and Fig. 4 is a view in perspective of one of the leaves, detached, of the hinge as herein included.

As disclosed in the accompanying drawings, R denotes conventional rockers supporting the chair structure C including a seat S provided with the arm rests A and 1 denotes a bracket secured to the under surface of the seat S at one side thereof and 50 adjacent its forward end, said bracket having the upper horizontal portion 2 extending a predetermined distance laterally from the seat S.

F denotes a fan of any ordinary or preferred type including the stem or handle 3 having its lower or free end portion secured

to the leaf 4 of the hinge H, the second leaf 5 of the hinge being anchored through the medium of the rivets 6 or the like with the outer end portion of the horizontal part 60 or arm 2 of the bracket 1.

At a predetermined point inwardly of the pivotal connection between the leaves 4 and 5 of the hinge H, the horizontal arm or part 2 of the bracket 1 is provided with the opening 7 through which is directed the elongated rod 9. The rod 9 is substantially vertically disposed and has its lower end portion directed through the opening 10 produced in the laterally extending substantially horizontal portion 11 of the bracket 12 secured to one of the rockers R at a point substantially in alinement with the bracket 1 and said rod 9 is of such a length as to have its lower end extending below the bottom of the adjacent rocker R when the chair C is rocked rearwardly whereby it will be perceived that upon forward rocking movement of the chair, the resultant contact of the lower end of the rod 9 with the floor or 80 other surface upon which the chair is rested will force the rod 9 upwardly and cause the upper end of the rod to engage the under surface of the leaf 4 of the hinge H and swing the fan F upwardly and upon the 85 chair C being rocked rearwardly the rod 9 and the fan F will drop downwardly by gravity. By this operation, it will be perceived that the fan F will be oscillated so as to agitate the atmosphere sufficiently to 90 cool the occupant of the chair and to keep the immediate vicinity free of flies or other insects.

While I do not wish to be particularly understood as limiting myself as to the dimensions of the bracket 1 or the fan F together with its stem or handle 3, I find it of particular advantage in practice to have the horizontal portion or arm 2 of the bracket and the stem or handle 3 of such a length as 100 to have the outer end of the fan overlie the arm rest A when the fan F is at the limit of its downward movement. I also find it of advantage to secure to the outer end of the arm or horizontal portion 2 of the bracket 1 105 and preferably by the rivets 6 or other securing means, hereinbefore referred to, an end of the flat spring 14 having its inner end portion extending upwardly and across the pivotal connection between the leaves 4 and 5 of the hinge H and with which the stem or handle 3 is adapted to contact in its

upward movement whereby it will be perceived that the fan will be prevented from passing a vertical position and whereby downward movement of the fan S is assured.

5 While the leaves 4 and 5 may be constructed as desired, I prefer to employ the arrangement illustrated in the accompanying drawings wherein the leaf 4 is produced from a single strip of elongated metal bent 10 back upon itself to afford the barrel 15 and having the arms 16 overlying opposite faces of the stem or handle 3 whereby an effective connection with the handle or stem 3 is assured. The barrel 15, as herein disclosed, is 15 interposed between the transversely spaced barrel 17 carried by the leaf 5 and a conventional pintle 19. I also find it of advantage to have the upper end of the rod 9 provided with the enlargement or head 18 20 whereby the downward movement of the rod is limited and also affording an increased contacting surface.

It may be pointed out that with a device 25 constructed as above described, it is possible to render the fan inoperative by simply lifting the fan into such position that it will not be engaged by the head of the rod 9 when the rocker is rocked and furthermore that by lifting the fan f to an approximately vertical position it is an easy matter to retract 30 the rod 9 and disengage it from the member 11 and from the bracket so that the whole device may be rendered inoperative or the parts disassembled for packing. Again it is 35 to be noted that the spring 14 does not engage at all times with the shank of the fan formed by the hinged leaves 4 and the arms 16 but that it forms a limiting stop to the upward movement of the fan, this stop being yielding and intended to throw the fan back again but not with violence. The 40 spring simply yieldingly stops the upward movement of the fan, prevents it from going too far, and allows it to fall by nearly its own weight. If the spring 13 urged the fan downward throughout its downward movement, the fan would strike the arm A with 45 considerable force, making a very unpleasant noise and shortly wearing out the fan. 50 As it is, the fan rises more or less gradually and falls with nearly the natural motion of fanning.

From the foregoing description, it is 55 thought to be obvious that a fan constructed in accordance with my invention is of an extremely simple and comparatively inexpensive nature and is particularly well adapted for use by reason of the convenience and facility with which it may be assembled, and it will also be obvious that my invention is susceptible of some change and modification 60 without material departure from the principles and spirit thereof and for this reason I

do not wish to be understood as limiting myself to the precise arrangement and formation of the several parts herein shown in carrying out my invention in practice.

I claim:

1. A fan attachment for rocking chairs comprising a bracket adapted to be attached 70 to a rocking chair and extend laterally therefrom, a fan hingedly engaged with the upper face of the bracket, a rod loosely disposed through the bracket and having a head at its upper end limiting the downward 75 movement of the rod relative to the bracket, the upper end of the rod contacting with the under side of the shank of the fan, the fan having free movement away from the bracket independent of the rod, and means 80 separate from the fan and its shank for resiliently limiting the movement of the fan in the last named direction.

2. The combination with a rocking chair, 85 of a bracket extending laterally therefrom, a fan having a shank hingedly engaged with the bracket, the fan normally lying upon the face of the bracket, a rod supported by the chair for vertical movement and having its upper end passing loosely through the 90 bracket and formed with a head contacting with the shank of the fan, said fan and its shank having independent vertical movement with relation to said rod, and resilient means for limiting the upward movement of 95 the fan.

3. The combination with a rocking chair having a seat and an arm, of an angular bracket attached to the seat extending laterally therefrom, then upward to approximately the level of the arm and then laterally outward, a guide member mounted upon the rocker of the chair and extending laterally therefrom, a fan having a shank hingedly connected to the upper face of the lateral projection of the bracket, the fan normally lying upon the arm of the rocker, a rod at its lower end passing through the guide member and at its upper end passing through the lateral projection of the 110 bracket and having a head disposed beneath but disconnected from the shank of the fan whereby the fan may have independent movement with relation to the rod, and a spring attached to the outer extremity of the 115 bracket extending upward and inward over the hinged connection of the shank of the fan to the bracket and resiliently limiting the upward movement of the fan.

In testimony whereof I hereunto affix my 120 signature in the presence of two witnesses.

JAMES E. NISBET.

Witnesses:

W. E. LAWSON,

ROBERT M. SUTPHEN.
